ALLIE G. GARBUTT, OF STATEVILLE, GEORGIA.

AIR-VALVE FOR INTERNAL-COMBUSTION ENGINES.

1,101,920.

Specification of Letters Patent. Patented June 30, 1914.

Application filed July 16, 1913. Serial No. 779,322.

To all whom it may concern:

Be it known that I, ALLIE G. GARBUTT, a citizen of the United States, and a resident of Stateville, in the county of Echols and State of Georgia, have made certain new and useful Improvements in Air-Valves for Internal-Combustion Engines, of which the following is a specification.

My invention relates to internal combustion engines, my more particular purpose being to provide a valve to be connected with such engines, and preferably mounted upon the manifold pipe thereof, for controlling, or at least modifying, the air supply.

More particularly stated, I seek to provide such a valve, automatic in its action, as may be controlled by the degree of vacuum obtaining in the manifold pipe, so as to increase the air supply as the vacuum diminishes, and to diminish the air supply as the vacuum increases.

Reference is made to the accompanying drawings forming a part of this specification and in which like letters indicate like parts.

Figure 1 is a fragmentary elevation of an internal combustion engine upon which my device is mounted. Fig. 2 is a vertical section through my improved valve showing the same as it appears with the engine running under ordinary conditions of load. Fig. 3 is a detail showing in elevation the plunger and the valve spring. Fig. 4 is a section on the line 4—4 of Fig. 2 looking in the direction of the arrow and showing the valve as it appears when the engine is stopped. Fig. 5 is a section similar to Fig. 4, but showing the valve as it appears when the engine is starting into action.

The engine cylinders are shown at 6, and at 7 appear the branches of the manifold pipe shown at 8. The manifold pipe is connected with a throttle 9, which in this instance is of the butterfly type, this throttle forming practically the outlet of the carbureter, which is shown at 10. The casing of my improved valve is shown at 11 and is provided with a nipple 12 having a threaded portion 13 to facilitate the connection of the casing with the manifold pipe 8. The casing is provided with a compartment 14 and with an annular shoulder 15. The casing at its upper end is provided with a threaded portion 16, and fitting upon the latter is a cap 17 provided with a vent hole 18. The casing 11 is further provided with a number of holes 19 all disposed in the same horizontal

plane, and radiating outwardly. An adjusting screw 20 extends through the bottom of the casing and is provided with a head 21 whereby it may be turned, and thus adjusted in the general direction of the length of the screw. A nut 22 is threaded to fit the screw, and serves the purpose of a lock for the same. A spring 23, wound into the proximate form of a cone frustum, is located within the casing and engages the adjusting screw 20. A valve plunger is shown at 24 and is provided with air holes 25 and with a groove 26 into which the air holes merge. The groove 26 is of substantially the same width as the maximum diameter of any one of the holes 19. The valve plunger 24 is hollow and is provided with an annular web 27 which engages the spring 23. This spring is so proportioned that the pressure exerted by it increases quite rapidly with the compression of the spring.

When the various parts of the valve are in normal position, or in other words, when the engine is standing still, the valve appears as indicated in Fig. 4, the plunger 24 being in its uppermost position and the air holes 19 being closed. Fig. 5 shows the relative positions of the various parts when the valve is subjected to the conditions obtaining when the vacuum in the manifold pipes is at its maximum, as for instance when the engine is being started, or when the engine is running from its own momentum and the throttle is closed.

Fig. 2 shows the relative positions of the various parts of the valve when the engine is running under normal conditions of load and when the vacuum in the manifold pipe is relieved to a considerable extent, owing to the fact that the throttle is now open to a commensurate degree.

The operation of my device is as follows: The tension of the spring 23 is adjusted by adjustment of the bolt 20, according to the needs of the engine, the character of work to be performed, and various other considerations such as may by experience be indicated as proper. The engine is now started and for this purpose the throttle 9 is open to a very slight extent. The first explosion in one of the cylinders 6 results in a partial vacuum being formed in the manifold pipe and as this explosion is followed rapidly by others, the vacuum in the manifold pipe suddenly becomes very great. The plunger 24 is thus drawn downwardly owing to air

pressure upon its upper surface, as will be understood from Fig. 2. The spring 23 is thus compressed and the valve 24 takes up the position indicated in Fig. 5. The holes 5 19 are thus closed and the engine receives no air except what is contained in the explosive mixture from the carbureter. This mixture, is well known in this art, as comparatively rich in fuel, but contains comparatively little air. As the engine develops speed and power, the throttle 9 is opened gradually manually. The vacuum in the manifold pipe 8 becomes correspondingly lessened. The air pressure upon the valve 10 plunger 24 being thus diminished the plunger, under control of the spring 23, gradually rises into the position indicated in Fig. 2. As the engine assumes normal working conditions, the plunger 24 settles 15 into such position that the supply of air through the holes 19, groove 26 and holes 25 is adequate for the work being done, and is proportional to the air pressure within the manifold pipe. When the engine is brought 20 to a stop—that is, when the throttle 9 cuts off communication between the carbureter 10 and the manifold pipe 8—the valve plunger 24 rises into its normal position as indicated in Fig. 4. When the engine is 25 first started, and consequently when the valve plunger 24 first moves downward, it of course brings the holes 26 into registry with the holes 19, but the downward movement of the valve plunger is so rapid that 30 the registry of the holes as just mentioned is not maintained more than a small fraction of a second. In practice, the valve plunger 24 drops downwardly and lodges upon the seat 15 as soon as an explosion 35 takes place in any one of the cylinders 6.

The device above described is very economical in the use of fuel, in that it automatically apportions the air supply to the needs of the engine.

40 In starting the engine the explosive mixture should be rich in fuel and poor in air. After starting, as the engine gradually assumes normal conditions of work, the air supply should be increased in the interest 45 of economy so as to render the combustion more thorough. Experience shows that as the engine develops speed and power, an increase in the air supply over that necessary for starting, is promotive of economy. More 50 than this, I find from actual trial that other desirable results are obtained. For instance, the deposit of carbon upon the spark plugs and various other parts where it is 55 ordinarily likely to occur, is prevented, or 60 at least greatly lessened by the use of this invention.

In an ordinary internal combustion engine of the kind used for propelling automobiles with the engine running idle from 65 the momentum of the machine, or even when

the machine is running lightly without any load, the pipe frequently reaches a degree of pressure designated in this art as a 20-inch vacuum. Contrary to the popular idea the vacuum in the manifold pipe is greater 70 when the engine is running with the throttle completely or almost closed than when the engine is developing considerable power. I take advantage of the difference in vacuum pressure in the manifold pipe in order to 75 enable such vacuum pressure to control automatically the supply of air to the engine. My improved valve controls this air supply, not by regulating directly the proportion of air supplied by the carbureter as a part of 80 the explosive mixture, but rather by introducing additional quantities of iron from an auxiliary source, and causing the same to mingle with the explosive mixture from the carbureter.

I find that the admission of air by the automatic action of my improved valve causes a thorough admixture to take place, not only between the air admitted and the contents of the manifold pipe, but between 90 the different ingredients of the mixture already within the manifold pipe before the additional air is admitted.

I do not limit myself to the precise construction shown, as variations may be made 95 therein without departing from the spirit of my invention.

I claim:

1. A device of the character described, comprising a manifold pipe, means for 100 maintaining a partial vacuum therein, a casing connected by a single passage with said manifold pipe, said casing being provided with a vent and with a compartment and further provided with a number of ports 105 disposed in the same plane and merging into said compartment, a valve slidably mounted within said casing and provided with a groove for registering with said ports, said valve being hollow and provided with a 110 number of holes extending inwardly from said groove, a spring engaging said valve, and an adjusting screw carried by said casing and engaging said spring for the purpose of adjusting the tension thereof upon 115 said valve.

2. A device of the character described, comprising a manifold pipe, a hollow casing communicating by a single passage with said manifold pipe, said casing being provided with a vent and with ports for inducting air, a valve slidably mounted within said casing and provided with a groove and with a number of holes merging into said groove, a spring engaging said valve, and means 120 controllable at the will of the operator for adjusting the tension of said spring.

3. A device of the character described comprising a manifold pipe, a substantially cylindrical casing communicating by a sin- 125

gle passage with said manifold pipe, said casing being provided with a vent and further provided with a plurality of ports for inducting air, said ports extending through the cylindrical wall of the casing and radiating outwardly from a common center, a valve slidably mounted within said casing and having generally the form of a cylindrical piston, said valve being provided exteriorly with an annular groove and further

provided with a number of ports merging into said groove and radiating inwardly therefrom, a spiral spring engaging said valve, and means controllable at the will of the operator for adjusting said spiral spring. 15
